UNITED STATES PATENT OFFICE.

CHARLES J. DORRANCE, OF CHICAGO, ILLINOIS.

FURNACE-GRAVE.

No. 840,609.

Specification of Letters Patent.

Patented Jan. 8, 1907.

Application filed January 18, 1905, Serial No. 241,568.

To all whom it may concern:

Be it known that I, CHARLES J. DORRANCE, a citizen of the United States, and a resident of the city of Chicago, in the county of Cook 5 and State of Illinois, have invented certain new and useful Improvements in Furnace-Grates; and I do hereby declare that the following is a full, clear, and exact description of the same, reference being had to the accompanying drawings, and to the letters of reference marked thereon, which form a part of this specification.

This invention relates more particularly to a shaking or rocking furnace-grate of the 15 class set forth in my prior patents for "Rocking or shaking grate-bar," issued to me May 14, 1889, No. 403,255, and "Movable grate-bar," issued May 5, 1891, No. 451,615. In 20 grates of this class as heretofore constructed the lever-arms on the grate-bars have been arranged at one side of the center of oscillation of the bar, and therefore have a tendency to lift the bar from its bearing, thus dumping a part of the fire into the ash-pit 25 and causing great inconvenience and trouble, frequently necessitating drawing the fire. Furthermore, the fuel varies in character and fineness, and frequently the fuel for 30 which the grate is particularly adapted is not so readily obtainable as a finer or a coarser grade, which may require for combustion a greater or less air-supply than the grate is constructed to afford. It is also of course important to so construct the grates as to prevent 35 the air-spaces between the parts thereof becoming clogged by the accumulation of cinders or clinkers, which would otherwise shut off a portion of the draft and seriously effect the operation of the furnace.

With these considerations in view the object of my invention is to afford a shaking or 40 rocking grate construction in which the air or draft spaces between the parts of the grate are capable of variation without the necessity of removing the grate-bars and to afford a grate construction providing a fuel-surface 45 comprising individual units so constructed and combined in relation with each other as to afford uniform draft-spaces between the 50 units.

It is also an object of my invention to so construct and support the grate-bars as to positively secure the same from lifting from 55 their bearings when operated and to permit

only the oscillating or rocking movement 55 characteristic of this construction.

It is a further object of my invention to afford a construction adapted to different widths of furnaces without necessitating the use of a longer grate-bar, but notwithstanding 60 extending the grates close to the side walls.

Lastly, it is an important object of this invention to afford a grate construction in which the operation of the grate acts to clean 65 the side and end walls of the furnace of clinkers and to prevent the accumulation of the same upon said walls of the furnace.

The invention embraces many novel features; and it consists in the matters herein- 70 after described, and more fully pointed out and defined in the appended claims.

In the drawings, Figure 1 is a fragmentary horizontal section of a furnace provided with a grate construction embodied in my invention, and in which a part of the fuel-surface has been removed. Fig. 2 is a longitudinal vertical section of the same. Fig. 3 is an enlarged fragmentary detail illustrating the operation of the grate. Fig. 4 is an enlarged 80 perspective view of one of the middle grate-bars embodying my invention. Fig. 5 is an enlarged fragmentary side elevation of the same, partly in section, illustrating the means of holding the grate-bar from lifting. Fig. 6 85 is a perspective view of one of the straddle-clips adapted to be carried on the end of the grate-bar over the bearing and projecting beyond the frame. Fig. 7 is a fragmentary perspective view showing a part of the grate-bar 90 with some of the single clips removed. Fig. 8 is a vertical transverse section of one of the single clips. Fig. 9 is a fragmentary section of the apertured stationary front grate-bar. Fig. 10 is a perspective view of a straddle-clip 95 embodied in my invention. Fig. 11 is an enlarged fragmentary view, partly in section, showing said clip in place. Fig. 12 is an enlarged fragmentary side elevation of one of the side rails or bars. 100

As shown in the drawings, the grate is supported upon a frame of any suitable construction comprising side rails or bars A A, which may be supported in the masonry of the arch, if preferred, or upon metallic or other legs A', 105 one of which is shown in Fig. 2 and which rests upon the floor or bottom of the ash-pit. Extending across and affording a support

and rigidly connecting the front ends of said side bars A is an end frame member or bar a. Supported upon the frame thus formed is a stationary front grate-bar A², which, as shown in Fig. 1, is of a length to extend into close proximity with the side walls and is provided on its front and rear sides with narrow slots therein, affording an air-inlet or draft-space therethrough. Resting on a ledge a⁴ or shoulder of suitable height on the inner side the fire-front is a dead-plate a', which is of a sufficient width to fill the space between said fire-front and the front side of the stationary grate-bar A², as shown in Figs. 1 and 2, thus affording a plane surface at the front end of the furnace over which the fuel is delivered to the grates. Said side frame members are provided at intervals, and at equal distances apart, with bearings upon which the grate-bars are journaled. As shown, said bearings comprise upwardly-directed bosses a², each having a concave bearing-seat in the top thereof and each provided on the inner side of the side frame member with an inwardly-directed lip a³, as shown in Fig. 5, thus affording an elongated bearing-surface.

Each of the grate-bars B to B⁷, inclusive, consists, as shown, of a cast or other bar of metal approximately rectangular in cross-section and plain for its entire length excepting at its ends, and, as shown, of greater vertical width at its middle part than at its end portions. As shown also, each of said grate-bars at its ends is provided with a cylindric journal b, which is parallel with the bar, but in advance thereof and integrally connected therewith by an angle-plate b⁵, as shown in Figs. 1, 3, and 4. On the outer end of said cylindric journal is provided a plate b', parallel with the angle-plate b⁵ and which extends rearwardly into alignment with the rear side of the bar and is provided on its outward side in alignment with the bar with a rib b², having a groove or seat at each side and at the top thereof, as shown in Fig. 4. A corresponding groove or seat is provided in a fillet b³ on the bar adjacent the angle-plate b⁵. A projecting lip b⁶, integral with the angle-plate b⁵, extends beneath said journal b and is adapted to fit closely to the lip a³ on the side frame, as shown in Fig. 5, and prevents the bar from being lifted from its bearings when operated.

Secured on each grate-bar and extending downwardly and forwardly therefrom to points directly below the bearings are one or more integral rocker-arms indicated on the bar B by b⁷ and b⁸, of which the rocker or shaking arm b⁸ is located near the middle of the bar B and the arm b⁷ near one end the same, and, as shown, the bars B², B⁵, and B⁷ or alternate bars are provided with corresponding rocker-arms b¹⁰, arranged in alignment therewith and connected by means of a

connecting-bar b⁹. A lever C is pivoted at its center on the leg or bracket A' and extends vertically, and a connecting-bar c connects the arm b⁷ with the upper end of the same. A bar c' connects the lower end of said lever with a rocker-arm c² on the grate-bar B⁴, and a connecting-bar C' connects alined rocker-arms c³ on the alternate grate-bars B⁴, B⁵, B³, and B⁶ intermediate the grate-bars connected by the bar b⁹. As shown, a shaker-bar D is pivotally engaged on the rocker shaker-arm b⁸ on the grate-bar B and extends forwardly through the fire-front of the boiler and is pivotally connected at its outer end to a lever d, the lower end of which is pivoted upon a bracket d', carried upon the fire-front, and the upper end of which is adapted for engagement with the shaking lever d². As shown also, a clip or bracket c⁴ is rigidly secured on the bracket or leg A' and extends upwardly and engages the inner end of the pivot-pin c⁵ of the lever C, the other end of which is engaged in said bracket or leg A'. Removably secured on each of said grate-bars are duplicate clips, some of which are single clips, as indicated by F, and some of which afford a grate-surface equivalent of a plurality of the single clips. These latter (indicated by E) are termed "straddle-clips," and, as shown, are cast or otherwise constructed to afford a convex fire-surface at the top, and comprise a central web provided at its extremities with integral downwardly-extending ends or legs e, each of which is provided with a central vertical slot therein open at the bottom and having the inner faces thereof shaped complementally with the groove or seats in the rib b² and fillet b³ on the grate-bar and adapted to engage therein, as shown in Fig. 1, covering the bearing. Each of said straddle-clips is provided on each side of the central web with laterally-directed projections e', as shown in Fig. 6, which taper outwardly and downwardly, thereby preventing material from becoming lodged therein.

The single clips, as shown, each comprise a casting of metal shaped to correspond with the end portions or legs of the straddle-clips and tapering from the top downwardly and also tapering from the center laterally to the ends of the clip, as shown in Figs. 7 and 8. Each of said clips is provided on one or both sides of the same adjacent the slot therein with a rib or projection f, which strengthens the same and affords means for spacing the single clips a uniform distance apart upon the grate-bar.

The operation is as follows: A furnace of any kind or construction and for any fuel may be provided with grates embodying my invention, and the same may be constructed of a width necessitating a single length of grate-bar or two or more grate-bars arranged end to end, as preferred; and it is obvious

where a plurality of such grate-bars are arranged end to end the straddle-clips on their adjacent ends will operate closely adjacent to each other without affording an intermediate space of sufficient width to interfere with successful firing. When the frame or side bars A are secured in place, either by securing the same in the masonry of the furnace or upon integral brackets or legs, as preferred, the grate-bars are dropped in place by turning the same first upon one side to permit the lip or projection b⁶ to slide beneath the lip a³ on the side frame member. When the grate-bar is swung to a vertical position or to any position the grate-bar is capable of assuming during normal operation, said lips or projections prevent the bar lifting, owing to their mutual engagement. The various connecting-bars and the shaking-bar are now secured in place pivotally, connecting the grate-bars so that alternate grate-bars are actuated by the same connecting-bars, and owing to the arrangement of the lever C and its connection with the grate-bars adjacent grate-bars are caused to rock oppositely, as shown in Fig. 3. The straddle-clips at one end of the grate-bar are now secured in place, covering the bearings, as shown in Fig. 1, and the single clips E are next dropped loosely in place upon each grate-bar, as shown in Fig. 7, and spaced the desired distance apart by means of a rib f or projection on each. Inasmuch as the single clips taper downwardly and laterally it is obvious that cinders, clinkers, or other material that might otherwise clog the fire having once passed below the top of the clip must fall freely therefrom into the ash-pit, thus insuring uniform draft-space at all times. This construction also enables the grate-surface to be varied at will to accommodate the furnace to different grades of fuel, inasmuch as the straddle-clips and all the single clips are quickly removable, thus permitting others to be substituted therefor. The substituted straddle-clips are constructed as before described, but afford a greater or less number of lateral projections e⁷, providing a less or a greater air-space, as desired. The thickness of the single clips of course will be varied to correspond with the straddle-clips, and the thickness of the ribs or projections f correspond with the thickness of the clip. With each installation clips adaptable for different classes of fuel may be furnished, and owing to the simplicity of the construction one set of clips may be removed and another substituted, thus adapting the grates for any kind of fuel.

60 By use of the straddle-clips shown in Figs. 10 and 11 a grate of a standard size can be used in a furnace considerably wider than would otherwise be possible, inasmuch as said clips are constructed as before described 65 with the addition of a lip or projection e⁸ on the outer end of the clip, extending the fire-surface longitudinally beyond the end of the bar into close relation with the furnace wall. Inasmuch as the straddle-clip positively engages the bar on each side the bearing this 70 projection may be of considerable width and may be constructed to afford a draft-space therethrough, if desired. In such an installation the side frame members being removed for some distance from the side walls 75 of the furnace permit the ashes to drop therebetween without lodging, and the frame is thereby kept from corrosion and from heating.

In operation alternate grate-bars being 80 engaged with the same connecting-rods and said bars being pivotally supported upon bearings eccentric therewith and in advance of the grate-bar, in shaking the grate adjacent grate-bars move oppositely toward and 85 from each other, as shown in Fig. 3, the forward movement of the grate-bar elevating the fire-surface, while the rearward swing lowers the grate-bar, thus producing an undulating movement in the furnace which 90 causes the fuel to travel toward the rear end of the furnace and effectually slices the fire. Obviously also, inasmuch as the straddle-clips operate in close relation with the side walls of the furnace and the straddle and 95 single clip on the rear grate-bar swing in close relation to the bridge-wall of the furnace, the operation of the grate in shaking serves to remove or cut all cinder or clinker adhering to said wall therefrom, leaving the 100 walls clean.

Obviously the shape or construction of the grate-bar lends the constructions readily to a wide variation in the fire-surface and the draft afforded therethrough, and though I 105 have shown a particular form of bar and clips embodied in my invention I do not purpose limiting this invention otherwise than as necessitated by the prior art, as obviously many details of construction and operation 110 may be varied without departing from the principles of my invention.

I claim as my invention—

11. In a grate the combination with bearing-bars of rocking bars mounted thereon, each rocking bar being provided with grooves arranged on opposite sides of the bearing-bars and forming seats, and protecting and fuel-supporting clips straddling said bearing-bars and engaging said seats. 115

12. In a grate the combination with bearing-bars of rocking bars pivotally engaged, thereon and each provided with grooves on each side of the bearing-bars, a plurality of single clips engaged on the rocking bars intermediate the bearing-bars, a straddle-clip extending over each bearing and engaged in said grooves and means preventing said rocking bars lifting from their bearings when 125 rocking. 130

3. In a grate the combination with bearing-bars of transverse rocking bars having offset journals on each end thereof engaged on said bearing-bars and provided with a groove on each side of the journal, clips seated on said rocking bars intermediate the ends thereof and a straddle-clip seated in the grooves adjacent each journal and covering the same and extending beyond the bearing-bar into close proximity with the furnace-wall affording an extended fuel-supporting surface.
4. In a grate the combination with bearing-bars of grate-bars journaled thereon at equal distances apart and provided with a groove at each side of each bearing-bar, a straddle-clip extending over each bearing-bar and provided with downwardly-directed legs adapted to engage in said grooves, independently-removable clips engaged on the bar between the straddle-clips and together therewith affording a fire-surface and a projection on each end of the grate-bar extending beneath the bearing and acting to hold the grate-bar from lifting from its bearings when operated.
5. The combination in a furnace-grate, of rigidly-supported side frame members, parallel grate-bars journaled eccentrically thereon at their ends and provided with seats at each side of the bearing-bars, straddle-clips engaged in said seats and straddling said bearing-bars, interchangeable duplicate clips carried on and projecting above the bars and affording a fire-surface, means for shaking the grate and a projection on each end of each grate-bar extending beneath the bearing and holding the bar from lifting when shaken.
6. In a furnace-grate the combination with rigidly-supported side frame members having bearings therein of grate-bars spaced at equal distances apart and having offset journals at their ends adapted to engage in said bearings, and provided with grooves on each side of the journal interlocking means acting to prevent the grate-bars lifting from their bearings when operated, bars connecting alternate grate-bars in sets, means connecting said sets and adapting them to move oppositely, a shaking-bar connected with one of said grate-bars and acting to swing adjacent bars oppositely in shaking the grate, straddle-clips having a slotted leg on each end adapted to engage the grooves in the grate-bars and single clips affording together with the straddle-clips a fire-surface removably secured on and projecting above said bars.
7. A grate-bar comprising a plain bar having forwardly-directed plates or knuckles at each end of the same and cylindric journals secured on said plates parallel with the bar, a plate engaged on the outer end of each journal, a straddle-clip covering the journal and projecting beyond the ends of the same, a lip or projection on one of said plates adapted to engage beneath the support for said bar and acting to prevent the bar lifting when shaking the grate.
8. In a grate construction the combination with a frame of parallel grate-bars having journals therein engaged in bearings in said frame, single clips on the bars intermediate the journals, straddle-clips removably engaged on the ends of the bars and covering the journals and provided with a lip projecting beyond the end of the bar and into close relation with the furnace-wall.
9. In a grate construction the combination with side supporting members of grate-bars journaled on and projecting beyond the same an offset journal on each end of the bar and a groove on each side of each journal, straddle-clips covering the journals and engaged at their ends in said grooves, and provided with a projection on the outer end of each adapted to extend the clip close to the furnace-wall and intermediate clips supported on the bar between the straddle-clips.
10. In a device of the class described the combination with a grate-bar having offset journals at the ends thereof and having a groove on each side of the journal, a plurality of clips supported on the bar between the journals, a straddle-clip covering each journal and comprising a central web and having lateral projections extending into close proximity with the furnace-walls and a leg on each end of said clip adapted to engage in the grooves on the opposite side of the journal.
- In testimony whereof I have hereunto subscribed my name in the presence of two subscribing witnesses.
